CLAIM

The ornamental design for a lawn sprinkler head, as shown and described.

DESCRIPTION

FIG. 1 is a perspective view taken from the top, front and right side of a lawn sprinkler head showing our new design;

FIG. 2 is a front elevational view thereof;

FIG. 3 is a left side elevational view thereof;

FIG. 4 is a right side elevational view thereof;

FIG. 5 is a rear elevational view thereof;

FIG. 6 is a top plan view thereof; and

FIG. 7 is a cross-sectional view taken on line 7—7 of FIG. 3.

The fragmentary broken line representation of a sprinkler base in FIG. 1 is for the purpose of illustration only.

FIG. 1

FIG. 2
